UNITED STATES PATENT OFFICE

JOSEPH H. SWEENEY, OF NASHVILLE, TENNESSEE

CORPSE HEAD SUPPORT FOR UNDERTAKERS

Application filed September 23, 1930. Serial No. 483,865.

This invention relates to improvements in head supporting and holding devices for use by undertakers in preparing bodies for burial.

5 The primary object of the present invention is to provide a head support which may be employed for holding the chin of the head in a predetermined position so that the upper and lower jaws may be held firmly together, enabling the embalmer to perform certain necessary massaging operations during the injection of the embalming fluid.

Another object of the invention is to provide a head support for corpses having a 10 clamping device for engaging and holding the skull at the sides thereof so that a section of the top of the skull may be removed for the performance of post-mortem examinations.

20 The present invention constitutes an improvement upon the structure disclosed in the Patent No. 1,815,171, issued July 21, 1931.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

25 In the drawings:

Figure 1 is a view in side elevation of the head rest embodying the present invention showing in dotted lines the position assumed by a head resting thereon.

30 Figure 2 is a view in top plan of the head rest and clamping device.

Figure 3 is a sectional view taken on the line 3—3 of Figure 2.

35 Figure 4 is a sectional view taken on the line 4—4 of Figure 2.

Referring more particularly to the drawings wherein like numerals of reference indicate corresponding parts throughout the several views, the numeral 1 indicates generally the top of the head rest embodying

the present invention which, as shown, is in the form of a flat rectangular frame 2 in which is formed a pair of bars 3 which are disposed in spaced parallel relation as shown and are substantially parallel with the side bars 4 of the frame. The bars 3 are connected intermediate their ends by a transverse bar 5 which is curved downwardly as shown in Figure 4 so as to receive the back of the head.

55 The side rails 4 of the frame are each provided with a longitudinally extending slot 6 which, at its forward end, opens into an enlarged opening 7.

60 Supported upon each side rail 4 is a post 8 which has a downwardly extending pin 9 which passes through the underlying slot 6 to receive a thumb screw 10 which may be drawn up against the underside of the overlying side bar 4, in the manner shown in Figure 4. The upper part of each post 8 is in the form of a semisphere 11, the flat face of which is directed outwardly with respect to the frame and has a threaded passage 12 formed therein.

65 Positioned against the flat face of the semispherical portion 11 of each post 8 is the flat surface of a similarly formed semisphere 13 which forms the terminus of a leg 14 of a substantially U-shaped frame which is indicated as a whole by the numeral 15, the yoke portion of which, which connects the legs 14, being indicated by the numeral 16. A screw 17 passes through each of the semispheres 13 for threaded engagement in the 70 bore 12 of the adjacent fixed semisphere so that, as will be readily seen, the frame 15 may be oscillated in a vertical plane and held in any desired adjusted position. As shown in Figure 1 this frame 15 extends across the

75 throat of the corpse whose head rests upon the support so that the yoke portion or bar 16 of the frame extends under the chin. Intermediate its ends this bar 16 has a screw 18 threaded therethrough, the forward end of which has a button 19 swiveled thereon, for contact with the chin of the corpse in the manner shown.

80 The frame 2 is supported upon the legs 20, in the lower end of which is threaded an 85

adjustment screw 21 by means of which the height of the frame may be adjusted.

At the forward part of the frame there is disposed thereacross the flat bar 22 which, at one end, is turned upwardly as indicated at 5 23. This bar adjacent each end is provided with a threaded pin 24 which passes downwardly through the underlying slot 6 and receives a thumb nut 25, which may be drawn up against the under surface of the bar 4 through which it passes to hold the bar 22 in a desired position on the frame.

This bar 22 supports a pair of clamp jaws, one of which is fixed and is indicated by the 15 numeral 26, while the other is shiftable and is indicated by the numeral 27. Each of these clamp jaws as shown is bowed slightly to generally conform to the curvature of the skull, the concave portions, of course, being in opposed relation as shown in Figure 3 so as to receive the skull therebetween. The shiftable jaw 27 carries an elongated base 28 which is disposed longitudinally of the bar 22 over a longitudinally extending slot 29 formed in the bar. A screw 30 extended upwardly through the slot 29 into the base 28, maintains in position against the underside of the bar 22 a plate 31 which, while it prevents the removal of the clamp jaw 27, permits it to be moved longitudinally upon the 25 supporting bar. The base 28 of the jaw 27 has an upturned end portion 32 which, as shown in Figure 3, is disposed between the jaw 27 and the upturned portion 23 of the bar 22. A screw 33 passes through and is in threaded engagement with the upturned portion 23 of the bar 22 and has its inner end extended through an aperture in the upturned portion of the jaw base 28, the connection of the screw with the portion 32 of the 30 jaw base being in the form of a swivel, the screw being prevented from moving through the aperture of this portion of the base by washers 34 carried thereby.

The opposite end of the screw 33 is in the 45 form of a crank 35 by means of which the rotation of the screw is facilitated and consequently the movement of the jaw 27 inwardly or outwardly effected.

From the foregoing description it will be readily seen that when the head of a corpse is placed upon the support, in the manner shown in Figure 1, the jaws 26 and 27 of the clamping device may be brought together 50 to engage the sides of the skull and firmly hold the same in position so that the necessary embalming operations may be performed thereon, and at the same time the frame 15 may be adjusted to the proper position so 60 that the screw 18 can be brought into firm contact with the chin so as to maintain the jaws of the corpse in contact.

Having thus described my invention, what I claim is:—

65 1. A head support of the character de-

scribed, comprising a base frame having side bars each provided with a longitudinally extending slot, an adjustable post mounted upon each side bar and having a portion extended through the adjacent slot to receive a securing screw, a frame of substantially U-shaped configuration having the free end of each leg thereof pivotally attached to a post, and a screw member carried by said frame for contact with the chin of a head resting upon the support.

2. A head support of the character described, comprising a base frame having side bars each provided with a longitudinally extending slot, an adjustable post mounted 70 upon each side bar and having a portion extended through the adjacent slot to receive a securing screw, a frame of substantially U-shaped configuration having the free end of each leg thereof pivotally attached to 75 a post, and a screw member carried by said frame for contact with the chin of a head resting upon the support, and means carried by the base for securing the head against movement thereon.

3. A head support for corpses, comprising a base in the form of a frame having side bars each provided with a longitudinally extending slot, bars within the frame for the support of the head, a frame having leg members, posts adjustable in said slots and each having pivotal connection with a leg member of said frame, a chin engaging screw carried by said last frame, a clamp comprising a pair of jaws, one shiftable relative to the other, said clamp being supported upon the side bars of the first mentioned frame, and means for adjustably securing said clamp in position upon the support, said means engaging in said slots for guidance thereby.

4. A head support for corpses, comprising a leg supported frame having oppositely positioned side bars each provided with a longitudinally extending slot, a bar disposed transversely of the frame and extending across said slots, pins carried by said bar and extending through the slots, thumb screws threaded upon said pins for engagement with the adjacent bars of the frame to maintain the transverse bar in adjusted position thereon, a clamp jaw fixed upon said last mentioned bar, a clamp jaw mounted upon the last mentioned bar and adjustable longitudinally thereon, and threaded means supported by the jaw supporting bar and having engagement with said shiftable jaw for effecting the adjustment thereof relative to the fixed jaw.

5. A head support, comprising a base, a head clamp consisting of a pair of jaws, one being fixed relative to the other, means connecting and supporting the clamp jaws upon the base, and means for securing the jaw supporting means in an adjusted position on the base.

6. A head support, comprising a base, a bar disposed transversely of the base, a clamp structure mounted on said bar and consisting of a pair of jaws, one of the jaws being movable longitudinally of and on the bar, said bar being mounted for movement in a horizontal plane on the base and means for securing the bar in an adjusted position upon the base.
- 10 7. A head support, comprising a base, a bar member mounted upon the base and disposed transversely thereof, a clamp structure carried by the bar and consisting of a pair of jaws, one of which is movable relative to the other, and a screw member supported by the bar and having connection with the shiftable jaw for moving the same relative to the fixed jaw.
- 15 8. A head support, comprising a base, a bar disposed transversely of the base and having one end turned upwardly and provided with a threaded aperture, a clamp member consisting of a pair of jaws mounted upon the bar, the jaw adjacent the up-turned end of the bar being shiftable longitudinally thereof, and a screw member threadably extended through the aperture in the up-turned end of the bar and having swivel connection at its inner end with the adjacent shiftable
- 20 30 jaw.
9. A head support, comprising a base having a pair of spaced parallel side bars each having a longitudinal slot therein, a bar member disposed transversely of the base and resting upon said side bars, a clamp comprising a pair of jaws mounted upon said transverse bar, one of said jaws being movable relative to the other, means for shifting the movable jaw, and guide and securing elements carried by the transverse bar and extending through the side bar slots for retaining the transverse bar in an adjusted position.
- 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835
- 55 In testimony whereof I hereunto affix my signature.

JOSEPH H. SWEENEY.
